UNITED STATES PATENT OFFICE.

EDWIN C. BALLMAN, OF ST. LOUIS, MISSOURI.

CENTRIFUGAL SWITCH.

Application filed October 8, 1924. Serial No. 742,295.

This invention relates to centrifugal switches, and more particularly to such switches as are used on electric motors for the purpose of changing the winding connections as the speed changes.

One of the objects of this invention is to provide a centrifugal switch of novel construction provided with make and break contacts which will protect the main contact surfaces from corrosion due to arcing.

Another object is to provide a switch of this type which will be simple and economical to manufacture and which will be rugged and durable in service.

15 Further objects will appear from the detail description taken in connection with the accompanying drawing, in which:

Figure 1 is a face view of a switch embodying this invention as seen from the end 20 of the motor shaft;

Figure 2 is a similar view of part of the switch showing the contacts in contacting position; and

Figure 3 is a section on line 3—3, Figure 25 1.

Referring to the accompanying drawing, 1 designates a frame or base upon which the various switch parts are mounted. This frame is provided with a central opening 30 surrounded by an inturned flange 2 adapted to be fitted to the motor shaft 3 for mounting the switch thereon as shown in Figure 3. The frame 1 is provided with a peripheral rim or flange 4. Mounted on but insulated 35 from the rim 4 is a series of relatively fixed contacts 5 provided with binding screws 6 at which the necessary connections to the motor winding may be made.

In the embodiment illustrated, three pairs 40 of contacts 5 are provided which are adapted to handle three motor circuits. Between each pair of contacts there is mounted a radially disposed rod 7. This rod is fitted into suitable perforations in the rim 4 and the 45 flange 2 and is held in place by a locking plate or keeper 8 engaging a reduced shoulder 9 on the rod 7, the plate or keeper 8 being slotted to fit said shoulder. Mounted to slide on and be guided by the rod 7 is a main 50 bridging contact 10 substantially U-shaped and having its contacting ends 11 arranged to face the contacts 5. Similarly mounted on the rod 7 to be guided thereby is an auxil-

iary bridging contact 12 which fits snugly over the contact 10 but has its contacting 55 tips 13 extending beyond the tips 11 of the main contact. The auxiliary contact 12 is entirely independent of the main contact 10, except that its movement is controlled by said latter contact. A spring 14 surrounds 60 the rod 7 bearing at one end against the keeper 8 and serving to hold the same against dislodgment and at the other end against the main contact 10 so as to maintain the same as well as the auxiliary contact 12 against the flange 2 and out of contacting position.

The springs 14 are adjusted in tension so that when the motor attains a predetermined speed, the contacts 10 and with them 70 the contacts 12 will move radially outwardly along and be guided by the guide rod 7 so as to bridge the contacts 5. The movement of the contact 10 is restrained by the spring 14 and the movement of the contact 12 is 75 controlled by that of the contact 10. Since the ends 13 of the auxiliary contact extend beyond those of the main contact 10, these ends 13 will make contact with the contacts 5 before the ends 11 come into contact therewith. As the speed of the motor falls off, the reverse of these operations will take place. The tension of the springs 14 will first overcome the centrifugal force of contact 10 and force the same away from the 80 contacts 5. Afterward the contacts 10 will come into engagement with the contacts 12 and move the same inwardly against the flange 2. In this way the auxiliary contact 12 makes contact with the contacts 5 before 85 90 and breaks contact after the engagement of the main contact 10. Therefore, since the circuit is made and broken at the tips 13, these tips will take all the pitting and corrosion incident to any arcing which may 95 take place. Such corrosion would also occur on the contacts 5 at a point spaced from that at which the tips 11 engage.

Since this switch is mounted on the motor shaft adjacent the motor winding 15 the 100 switch would have a tendency to shield the winding from ventilating air currents. In order to overcome this effect, the frame 1 is provided with ventilating openings which may have inturned flanges 16. These openings permit the passage of air through the 105

frame 1 to the motor winding. On account of the fanning action of the winding itself there will ordinarily be established a distinct suction effect tending to pass the air through these openings and radially outward through the winding. The flanges 16 may assist in producing a fanning action in order to additionally promote ventilation of the winding.

10 It will be seen that in accordance with this invention a switch is provided which may be mounted on the shaft of an electric motor for the purpose of controlling the circuits thereof, which has a simple structure 15 adapted for making and breaking the contact on a set of auxiliary contacts, while the main circuit is maintained by a main bridging contact which is protected against corrosion by arcing. The auxiliary contact makes 20 the circuit first and breaks it after the main contact. The point of making and breaking is also spaced from the point of maintaining the circuit on the fixed contacts 5. The spring 14 may be adjusted so that all the 25 contacts will act simultaneously to handle a plurality of circuits at the same time or they may be adjusted to act successively for performing short circuiting operations in the same circuit.

30 The installation of such a switch will not interfere with the ventilation of the motor since the ventilating openings which are uniformly spaced around the switch frame not only permit the circulation of air to the 35 winding but even assist in promoting a circulation.

It is obvious that various changes may be made in details of construction without departing from the spirit of this invention; 40 it is, therefore, to be understood that this invention is not to be limited to the specific details shown and described.

Having thus described the invention, what is claimed is:

45 1. A centrifugal switch for electric motors, comprising, a supporting frame mounted on the motor shaft, relatively fixed contacts on said frame, a main bridging contact having a plurality of make and break terminals 50 centrifugally movable on said frame and adapted to make and break contact with a plurality of said fixed contacts, and an auxiliary bridging contact movable with said main contact and adapted to bridge said 55 fixed contacts before said main contact.

2. A centrifugal switch for electric motors, comprising, a supporting frame mounted on the motor shaft, relatively fixed contacts on said frame, a main bridging contact having a plurality of make and break terminals 60 centrifugally movable on said frame and adapted to make and break contact with a plurality of said fixed contacts, and an auxiliary bridging contact movable with but 65 regulated by said main contact and adapted

to bridge said fixed contacts before said main contact.

3. A centrifugal switch for electric motors, comprising, a supporting frame mounted on the motor shaft, relatively fixed contacts on 70 said frame, a main bridging contact having a plurality of make and break terminals centrifugally movable on said frame and adapted to make and break contact with a plurality of said fixed contacts, and an auxiliary bridging contact movable with and fitting said main contact and adapted to bridge said fixed contacts before said main contact.

4. A centrifugal switch for electric motors, 80 comprising, a supporting frame mounted on the motor shaft, relatively fixed contacts on said frame, a main bridging contact having a plurality of make and break terminals 85 centrifugally movable on said frame and adapted to make and break contact with a plurality of said fixed contacts, and an auxiliary bridging contact movable with said main contact and adapted to contact independently with said fixed contacts. 90

5. A centrifugal switch for electric motors, comprising, a supporting frame mounted on the motor shaft, relatively fixed contacts on said frame, a main bridging contact centrifugally movable on said frame and adapted to make and break contact with a plurality of said fixed contacts, and an auxiliary bridging contact movable with said main contact, and adapted to make independent 95 centrifugal contact with said fixed contacts. 100

6. A centrifugal switch for electric motors, comprising, a supporting frame mounted on the motor shaft and having a rim, relatively fixed contacts on said rim, a radial guide on said frame, a main bridging contact centrifugally movable along said guide to bridge certain of said fixed contacts, and an auxiliary bridging contact centrifugally movable along said guide to contact with 105 said certain fixed contacts. 110

7. A centrifugal switch for electric motors, comprising, a supporting frame mounted on the motor shaft and having a rim, relatively fixed contacts on said rim, a radial guide on said frame, a main bridging contact centrifugally movable along said guide to bridge certain of said fixed contacts, and an auxiliary bridging contact centrifugally movable along said guide to contact with said 115 certain fixed contacts, said auxiliary contact extending beyond said main contact. 120

8. A centrifugal switch for electric motors, comprising, a supporting frame mounted on the motor shaft and having a rim, relatively fixed contacts on said rim, a radial guide on 125 said frame, a main bridging contact centrifugally movable along said guide to bridge certain of said fixed contacts, and an auxiliary bridging contact centrifugally movable along said guide to contact with 130

said certain fixed contacts, before said main contacts.

9. A centrifugal switch for electric motors, comprising, a switch support mounted on the motor shaft, a pair of relatively fixed contacts on said support, a plurality of centrifugally movable bridging contacts and

adapted to make and break contact with said pair of fixed contacts, one of said bridging contacts being adapted to bridge 10 said fixed contacts in advance of the other.

In testimony whereof I affix my signature this 14th day of August, 1924.

EDWIN C. BALLMAN.
